UNITED STATES PATENT OFFICE.

JOHN H. SHAW, OF NEW HAVEN, CONNECTICUT.

DESIGN FOR A DOLL-SHOE BOTTOM.

54,779.

Specification for Design.

Patented Mar. 23, 1920.

Application filed February 12, 1919. Serial No. 276,663. Term of patent 14 years.

To all whom it may concern:

Be it known that I, JOHN H. SHAW, a citizen of the United States, residing in New Haven, county of New Haven, State of Connecticut, have invented a new, original, and ornamental Design for a Doll-Shoe Bottom, of which the following is a specification when taken in connection with the accompanying drawing.

In the drawing:

Figure 1 is a front view of a doll shoe embodying my new design, the "upper" of the same being indicated in dotted lines.

Fig. 2 is a side view of the outer side face of the same.

Fig. 3 is a side view of the inner side face of the same, and

Fig. 4 is a rear end view of the same.

As shown in the drawing the leading feature of my design for a doll shoe bottom consists of a relatively thick shoe bottom or sole and heel combined, having its lower face cut away transversely to slope upwardly from the longitudinal outer edge thereof to the longitudinal inner edge; that is, the shoe bottom has its lower face cut away to slope from one marginal edge of the shoe bottom to the other marginal edge.

What I claim is:

An ornamental design for a doll shoe bottom as shown and described.

JOHN H. SHAW.
